OIL BURNING APPARATUS

Reginald W. Beckett, Rocky River, Ohio, assignor to Cleveland Steel Products Corp., Cleveland, Ohio, a corporation of Ohio

Application August 11, 1936, Serial No. 95,396

5 Claims.

(Cl. 158—4)

This invention relates to oil burning apparatus and more particularly to oil burning apparatus of the rotary type in which combustion of the fuel mixture is initiated adjacent the combustion chamber wall of the furnace.

One of the objects of the present invention is to provide new and improved oil burning apparatus of the rotary wall flame type which is so constructed that more efficient combustion of the fuel can be obtained.

Another object is to provide oil burning apparatus of the wall flame type with a fuel intercepting member of improved construction which is economical to manufacture and which is efficient in its operation.

A further object is to provide oil burning apparatus of the wall flame type with flame deflecting elements of new and improved construction.

With the above and other objects in view, which will be apparent from the following detailed description, the present invention consists in certain features of construction and combinations of parts to be hereinafter described with reference to the accompanying drawings, and then claimed.

In the accompanying drawings which illustrate a suitable embodiment of the present invention,

Fig. 1 is a side view of a furnace having the oil burning apparatus of the present invention incorporated therein, a portion of the furnace being shown in section.

Fig. 2 is an enlarged vertical elevation looking from the front of the furnace, but with the furnace being shown in section.

Fig. 3 is an enlarged horizontal section taken approximately on line 3—3 of Fig. 2, and with the fuel intercepting ring and deflector elements removed.

Fig. 4 is a perspective view of one of the flame deflecting elements.

Fig. 5 is a plan view of the oil burning apparatus taken approximately on line 5—5 of Fig. 1, and

Fig. 6 is a vertical section taken approximately at right angles to the view shown in Fig. 2.

Referring to the accompanying drawings in which like numerals refer to like parts throughout the several views, the present invention is shown incorporated in a furnace of the hot-air type. It is to be understood however, that the invention is also capable of being incorporated in furnaces of the steam and hot water type.

In a copending application Serial No. 93,395 filed on August 11, 1936, I have described in de-

tail the manner of mounting the oil burner unit in the furnace unit.

The furnace unit comprises an annular shell-like structure A within which the burner unit is assembled as a unitary structure, including a supporting base 1, having a horizontal top portion 2, depending side portions 3 connected by a depending rear portion 4 and an open front portion 4a. The supporting base 1, as shown in Figs. 1, 2 and 6 is supported on a bottom portion B of the furnace unit, the open end portion of the base 1 extending below and beyond a removable wall portion C of the furnace unit.

The top portion 2 is provided with an opening 5 therethrough substantially coaxial with the furnace chamber D, and seating upon the upper portion 2 is a sheet of insulation 6 having an opening 7 coaxial with the opening 5.

An annular plate 8 is supported by the sheet of insulation 6 and is provided at one portion with an arcuate extension 9 abutting the wall member C and at other portions with spaced radially extending portions 10 which abut the furnace wall to align the casting 1 within the furnace unit. The plate 8 is rigidly mounted by 25 means of bolts 11 extending through the insulation 6 and the top portion 2. The plate 8 also has an opening 12 coaxial with the openings 5 and 7, which opening is defined by an upwardly extending annular flange 13, the wall of the opening having inwardly extending projections 14.

Secured to the under side of the plate 8 is an annular shell 15, having a circumferential bottom flange 16, the securing bolts 17 therefor extending through the flange 16 and having their heads supported on the projections 14. The casting or shell 15 is provided with an apertured web 18 terminating in an annular hub 19, the apertures 20 of the web 18 forming air openings which are adjustably controlled by a shutter 21. The shutter 21 is rotatably supported by an annular member 22 extending through the hub 19 and supported thereon by a nut 23.

The plate 8 is also formed with concentric inner and outer upwardly extending flanges 24 and 25. Engaged with the radially outer surface of the flange 24 is an upwardly extending ring or band 26 of heat resistant metal and engaged with the radially inner surface of the outer flange 25 is a second ring or band 27 of heat resistant metal, which band is preferably of greater height than the band 26. The bands 26 and 27 are provided with L-shaped stampings 28 secured thereto which seat upon the plate 8 as shown in 55

Fig. 6. The annular space between the band 26 and shell 15 is filled with refractory 29 to a level below the upper edge of the band 26, and the annular space between the bands 26 and 27 is also filled with refractory 30 to a level, somewhat below the upper edges of the bands 26 and 27, as shown in Fig. 6.

The space between the support 1 and the walls of the furnace unit may, if desired be filled with a suitable insulation 31, such as, for example, mineral wool, and the annular space between the furnace wall and the outer band 27 is preferably filled with an insulation 32, such as, for example, asbestos flour.

15 Suspended from the shell 15 by means of brackets 33 is a driving motor 34 having a hollow shaft 35 projecting beyond the ends thereof. The upper end of the shaft 35 extends through the annular member 22 and is provided with a closure cap or head 37 which carries a plurality of radially extending tubes 38 that communicate with the hollow shaft 35. Secured to the head 37 by means of a cap nut 39 is a deflecting plate 40 having a plurality of fan blades 41 on its under side, the tubes 38 and plate 41 being disposed above the annular shell 15.

The lower end of the hollow shaft 35 is provided with a threaded member 42, the threads of which spiral in a direction opposite to the direction of rotation of the shaft 35. The member 42 is enclosed in a casing 43 and secured to the end of the motor 34 and has an inlet 44 which is connected by means of a conduit 45 with control valves 46 and a shutoff valve 47, which, in turn is connected with a suitable source of oil supply (not shown). The valves 46 and 47 are supported on a bracket 48 secured to a cross-piece 49 extending between the sides 3 of the support 1.

40 The cross-piece 49 also supports an electrical outlet box 50 and a transformer 51, the leads for the motor being connected with the outlet box connections and surrounded by a conduit 52.

45 Fitting within the outer band 27 is an endless fuel intercepting member 53 of heat resistant metal which seats upon the refractory 30.

50 Associated with the endless member 53 are a plurality of deflecting elements 54, each of which is preferably formed of a single piece of heat resistant sheet metal. Each of these elements is provided with a horizontal portion 55 having projecting end portions 56, which are bent downwardly at right angles and formed with narrow slots 57 therein. Each element 54 is also provided with an inner, solid side portion 58, which is inclined downwardly, and with narrow outer side portions 59, which are alternately inclined upwardly and downwardly as shown in Figs. 4 and 6.

55 The elements 54 are supported by the end portions 56 in closely spaced relation, the bottoms of the slots 57 seating on the upper edge of the ring 53, as shown in Fig. 6, the bottoms of the slots 57 spacing the horizontal portions 55 upwardly above the edge of the flame ring 53 to provide passageways 60 therebetween.

60 The fuel is preferably electrically ignited by means of electrodes 61 extending through the hearth portion and provided with terminals 62 connected by conductors 63 with the transformer 51, those portions of the electrodes which extend through the hearth being encased in suitable insulation material 64 mounted in preformed refractory segments 65 embedded in the refractory 29 adjacent the inner band 26.

65 Each electrode 61 extends to a region above the

endless member 53 and is formed with a reversely bent portion 66 having a tip 67 extending over the band 26 and terminating in spaced relation with respect to the flame ring 53 which is grounded. Each electrode is also inclined with respect to the radius of the band 26, as shown in Figs. 3 and 5, in the direction of rotation of the distributing unit, so that the electric sparks passing from the electrodes to the endless member 53 travel at least partially in the direction of air travel adjacent the endless member.

The band 26 is formed with a notch 68 which extends substantially to the refractory in advance of each electrode, as shown in Figs. 2 and 3, through which a portion of the air travels for 15 passage between the electrode tips and member 53.

When there is a demand for heat, suitable controls, not shown, start the motor 34 in operation and cause sparks to pass from the electrode tips 20 to the flame ring 53. The rotating head causes streams of air and oil to discharge against the flame ring 53 where the oil is ignited and burns from the annular space between the member 53 and band 26. The flame heats the member 53 25 and deflector elements 54 and as these become hot, the oil and air become atomized and mixed through impact with the endless element 53 and vaporized, due to the heat thereof. The vaporized gases travel upwardly and are deflected 30 through the passageways 60 by the solid inner portions 58 of the deflecting elements 54, into the space adjacent the wall A, where they are further broken up by the alternating elements 59, combustion thereof then being initiated at 35 the annular region adjacent the elements 59 and wall A. The elements 59 of the deflectors 54, after the burner is in operation, substantially assume a red glowing heat which materially assists in the vaporization of the gases and the 40 burning of the same against the wall of the furnace unit.

Due to the action of the fan blades 41, and the rotational movement of the air expelled thereby, the flame burning, during normal operation, from 45 the region of the elements 59 and the wall A has a circular, wall wiping movement. The flame produced is bluish in color and quiet.

While the bands 26 and 27, and the member 53 are shown as being of circular shape for use 50 in a circular combustion chamber, it is to be understood that they may be of oblong, square or rectangular shape, depending upon the shape of the combustion chamber in which the oil burner unit is to be used. Also, the mounting and supporting means for the casing 15 and motor 34 55 may be varied, it being understood that the member 53 and deflector elements 54 may be used in any type of furnace unit and with any air and oil distributing head capable of cooperating therewith and producing a flame of the character described.

Although a single embodiment of the invention has been shown and described it will be understood that numerous details of the construction shown may be altered or omitted without departing from the spirit of this invention as defined in the following claims.

What I claim is:

1. In oil burning apparatus of the rotary wall 70 flame type having an upright combustion chamber wall and a centrally disposed rotary means for discharging oil and air toward said wall, a hearth and flame producing structure comprising a hearth body disposed below the path of dis- 75

charge of the oil and air and extending from said rotary means to said wall, a one-piece, imperforate band of metal extending upwardly from said hearth for intercepting and, when heated, for vaporizing the oil discharged from said means, said band being of uniform inside diameter throughout its height and being spaced inwardly of said wall to provide an annular chamber therebetween, and horizontally arranged means disposed above said band in spaced relation for directing air and vaporized oil in a substantially horizontal direction outwardly over said annular chamber, said horizontally arranged means comprising a plurality of deflecting elements spaced in endwise relation with respect to each other, each of said elements including a continuous imperforate portion extending inwardly and downwardly with respect to said band and an integral continuous imperforate portion disposed at right angles to and overlying said band in spaced relation.

2. In oil burning apparatus of the rotary wall flame type having an upright combustion chamber wall and a centrally disposed rotary means for discharging oil and air toward said wall, a hearth and flame producing structure comprising a hearth body disposed below the path of discharge of the oil and air and extending from said rotary means to said wall, a one-piece, imperforate band of metal extending upwardly from said hearth for intercepting and, when heated, for vaporizing the oil discharged from said means, said band being of uniform inside diameter throughout its height and being spaced inwardly of said wall to provide an annular chamber therebetween, and horizontally arranged means disposed above said band in spaced relation for directing air and vaporized oil in a substantially horizontal direction outwardly over said annular chamber, said last mentioned means including imperforate portions extending inwardly beyond said band, and a plurality of fingers disposed in alternate upward and downward directions over said annular chamber, said fingers cooperating with said annular chamber to hold the flame of combustion downwardly adjacent said combustion chamber wall.

3. A vaporized oil and air mixing and deflecting device for oil burning apparatus of the rotary wall

flame type, comprising an imperforate portion having at one side an imperforate extension disposed at an angle thereto, and a plurality of fingers extending from the opposite side thereof at alternately opposite angles.

4. In an oil burning apparatus of the rotary wall flame type having an upright combustion chamber wall, an oil and air distributing device having a horizontal rotary head for projecting oil and air in a horizontal direction toward said wall, a hearth plate below said distributing device and having a central opening for said device, said plate having abutment means extending upwardly adjacent the periphery thereof, an endless band abutting said abutment means, refractory material on said plate at each side of said band terminating below the upper edge of said band, and a second endless band of metal closely abutting said first band and seating on said hearth material, said second band extending upwardly to intercept the oil and air distributed by said device.

5. In an oil burning apparatus of the rotary wall flame type having an upright combustion chamber wall, an oil and air distributing device having a horizontal rotary head for projecting oil and air in a horizontal direction toward said wall, a hearth member below said distributing device including a ring-like member extending upwardly adjacent the periphery thereof and in spaced relation with respect to said upright wall to provide an annular chamber therebetween and for intercepting and, when heated, for vaporizing the oil distributed by said head, and vapor directing means comprising a plurality of members supported on said ring-like member in endwise spaced relation, each of said members having an imperforate strip portion spaced above said ring-like member and at right angles with respect thereto, an integral second imperforate strip portion extending inwardly and downwardly with respect to the inner face of said ring like member and a plurality of narrow fingers extending outwardly beyond the outer face of said ring-like member, certain of said fingers extending downwardly into said annular chamber and certain of said fingers extending upwardly with respect to and over said chamber.

REGINALD W. BECKETT.
